Primary Examiner — Mary Ann Calabrese(57) **CLAIM**

We claim the ornamental design for a display screen with keyboard graphical user interface, as shown and described.

DESCRIPTION

FIG. 1 is a front view of a display screen with keyboard graphical user interface; and,

FIG. 2 is a front view of a display screen with keyboard graphical user interface showing an alternate embodiment thereof.

The broken lines showing of a display screen form no part of the claimed design.
